GENERATION OF HIGH PRESSURE STEAM
WITH LOW SALT CONTENTOtto Hartmann, Kassel-Wilhelmshohe,
GermanyApplication March 6, 1939, Serial No. 260,216
In Germany March 23, 1938

5 Claims. (Cl. 122—33)

This invention is directed to the generation of high pressure steam with a low salt content from a feed water containing so much salt as to make the water practically unusable.

It is an object of the invention to generate steam substantially free of salt from a feed water which contains a substantial quantity of salt, the steam being washed in the boiler in which it is generated.

A further object of the invention is to generate steam substantially free from salt from feed water containing salt by passing the steam bubbles formed in the feed water through a layer of purer water which substantially filters the salt from the generated steam.

A further object of the invention is to generate steam substantially free of salt by covering the feed water having a large salt content, and having a relatively high specific gravity, with a layer of water substantially free of salt and having a relatively low specific gravity, the steam evaporated in the feed water of high specific gravity being effectively washed and freed from salt in the layer of water of low specific gravity.

In the generation of high pressure steam, one of the principal problems is to obtain a steam which is substantially free of salt. It is, of course, understood that the salt carried along in dissolved or gaseous state by the steam evaporated in the boiler, deposits or precipitates on the nozzles and blades of a turbine, and that such deposits not only destroy the efficiency of the turbine, but also cause a destruction of the turbine through corrosive action. Various methods are employed to reduce the salt content of the generated steam, one common method being the condensing of the used steam and returning the water to the boiler, with only additional salt free feed water amounting to 3% to 5% being required. Washing drums have also been provided with high pressure boilers, the freshly generated steam being passed through these washing drums. Also the washing of the steam has been attempted by passing the freshly generated steam over surfaces wetted by fresh water in the boiler drum. These methods are not satisfactory because of the additional water required in the washing drums, and because of the heavy and expensive equipment necessary for condensers and washing drums as well as the large washing surfaces necessary. Obviously the additional equipment is expensive as well as being bulky and cumbersome. Furthermore, even with the use of these auxiliaries, it is almost necessary to use chemically pure feed water, the production

of which is, in itself, an expensive operation. Likewise, steam converters and other auxiliaries all have their disadvantages.

The problem is solved, according to the instant invention, by a very simple and effective means by which the principal feed water need not be chemically pure water. The method is especially advantageous in boiler systems where the steam is indirectly generated. In general, the feed water in the boiler is not circulated, and is only agitated by the steam bubbles being evaporated therein. The feed water, having a relatively high salt content, is contained in the lowest part of the boiler, and over top of this feed water, a layer of water substantially free of salt is placed. The water in this upper layer may be obtained from a condenser. The upper layer of water, being substantially pure, has a lower specific gravity than the feed water in the lower part of the receptacle, and consequently the two layers do not tend to mix. Under operating conditions the water in the upper layer is constantly replenished so that the upper layer is effectively maintained despite boiling. The steam bubbles evaporated in the lower layer of water pass through the upper layer of pure water, and in so passing, the steam is washed, giving up its salt. A boiler can have, according to this invention, 80% of the total water composed of water with a high salt content and forming the lower water layer, and 20% as pure water forming the upper layer. From such steam can be produced which has such a low salt content that no appreciable precipitation of salt takes place in the turbine. Although the method is usable in the direct generation of steam, it is especially advantageous in boilers using indirect generation of steam, inasmuch as the tubes of the primary steam generating system can be evenly distributed throughout the boiler of the secondary generating system, and thus a very uniform evaporation of the steam in the lower layer of high salt content water can take place. Indirect steam boilers such as the Schmidt-Hartmann boiler type, United States Patent No. 1,788,520, is especially adaptable for the instant method as the heating tubes for the secondary system are immersed in the water of the secondary system, and no disturbance of said water, except for rising steam bubbles takes place. The invention is also suitable for the Loeffler type boiler, United States Patent No. 1,740,524, the non-circulating water content of which is heated by blown-in superheater steam.

55 A means by which the objects of this inven-

tion are obtained is shown in the accompanying drawing; in which:

Fig. 1 is a boiler arranged according to the instant invention; and,

Fig. 2 is a cross sectional view on the line 2—2 of Fig. 1.

Fig. 1 illustrates the method applied to the secondary boiler of an indirect steam generating system.

Within the boiler 2 are placed tubes 4 which are connected by headers 6 and tubes 8 to the primary steam generating system. Feed water having a high salt content is fed to the lower portion of the boiler from pump 10 through pipe 12 to valve 14, and from valve 14 is admitted into and evenly distributed in the lower portion of the boiler by being passed through a perforated tube 16 extending the length of the boiler.

This feed water consists of a strong lye concentration from about 2° to 5° Bé. It is preferable to have this feed water of as high a salt content as practical, inasmuch as the difference in its specific gravity and the specific gravity of the pure feed water to be supplied above, prevents the two layers from mixing. It is noted that this layer or strata of feed water, which is denoted as *a* in the drawing, comprises substantially 80% of the water in boiler drum 2.

Substantially pure salt free feed water, which may be condensed steam, is forced from feed pump 20 through pipe line 22 into the upper portion of the boiler. Pipe line 22 connects with valve 24, from which the substantially pure feed water is passed into a flume 26, the water overflowing the sides of the flume to form a layer *b* of substantially pure feed water on top of the layer *a*. The layers *a* and *b* do not tend to mix because of the difference in specific gravity therebetween. The water in layer *b* should have about the same temperature as the generated saturated steam, so that the water in layer *b* will not sink down and mix with the water in layer *a*. However, the water in layer *b* can be colder, if the salt content of the water in layer *a* is increased. In the cold upper strata *b*, the salt rising in the steam bubbles from the layer *a* is not only dissolved and separated off, but the sublimated salts in gaseous state contained in the steam bubbles are solidified in the cold water and precipitated out. Furthermore, the substantially pure water comprising condensate in the layer *b* has the excellent property of not foaming during vaporization, while the high salt content of the layer *b* foams energetically, and were it not for the layer *b*, the foaming would fill the entire boiler. Thus the layer *b* has the further advantages of preventing foaming. The use of the perforated tube 16 and the flume 26 insures a good distribution of the water for each of the two layers through-

out the boiler, without danger of mixing the two layers. The steam generated is taken off through dry pipe 27 to a point of use through conduit 28.

5 The method described has the further advantage in that existing types of indirect steam generating boilers can be used with but slight changes. For example, boilers of the Schmidt or Löffler types need only be provided with the perforated tube 16 and the flume 26, the tube and flume being connected to separate supply systems of feed water. The cost of equipment is thus materially reduced, and the cost of washing the steam is further reduced because only a small part of the water fed to the boiler needs to be substantially pure salt free water.

Having now described my invention, what I claim and desire to secure by Letters Patent of the United States is:

20 1. A method of generating high pressure steam substantially free from salt in a boiler without circulating water comprising feeding water having a high salt content into the lower portion of the boiler, feeding water having a low salt content into the upper portion of the boiler as a layer covering said first fed water, and heating said boiler to form steam bubbles rising from said first fed water, said bubbles passing through and being washed in said second fed water.

25 2. A method as in claim 1, said second fed water being supplied to said boiler at a temperature lower than that of said first fed water.

30 3. A method as in claim 1, said heating comprising the heating in the secondary system of an indirect steam generating boiler.

35 4. A method of generating high pressure steam substantially free from salt in a boiler without circulating water comprising continuously feeding water having a high salt content into the lower portion of the boiler, continuously feeding water having a low salt content into the upper portion of the boiler as a layer covering said first feed water, heating said boiler to form steam bubbles rising from said first fed water, and removing the steam from said boiler after it has been washed by passing through said second fed water.

40 5. An apparatus for the generation of substantially salt free high pressure steam comprising a boiler, heating means in said boiler, first means for uniformly distributing a feed water of high specific gravity over the lower portion of said boiler, second means for distributing uniformly a feed water of low specific gravity over the feed water of high specific gravity, a first source of feed water having a high specific gravity, said first means being connected to said first source; a second source of feed water having a low specific gravity, and said second means being connected to said second source.

45 60 OTTO HARTMANN.
